JAMES J. SANTIAGO, OF LOS ANGELES, CALIFORNIA, ASSIGNOR TO JOHN GRANT, OF LOS ANGELES, CALIFORNIA

EXPANSIVE REAMER AND DRILL

Application filed December 27, 1927. Serial No. 242,747.

This invention has to do with expansive drills or reamers in general, and, in a specific and practical application, has more particularly to do with underreamers designed for reaming a well hole below the casing, and the invention is mainly concerned with a combined underreamer and drill using a pilot drill ahead of the reamer.

In that type of combination it has heretofore been proposed to use a reamer cutter, or a series of such cutters, offset to one side of the axis of rotation, it being expected that in passing down through the casing these offset cutters will find their own center in the casing to pass freely therethrough. In order to allow such cutters thus to pass through the casing it has been found necessary to arrange the drill bit, which is usually in the form of a flat fish tail bit, in a plane substantially at right angles to the plane of cutter offset. Emerging below the pipe, the tool is then expected to find and rotate upon the center of the drill hole in such a manner that the offset cutters will project far enough from the center of rotation to ream the hole. Such a tool, however, depends upon the fish tail bit as a pilot or guide and, with the bit disposed as it must be for passing down through the pipe, it is easily displaced laterally from the center of the hole or from the proper center of rotation, with the result that the whole tool tends to gyrate about the center of rotation and the reaming cutters do substantially no reaming.

The present invention is designed for the purpose of overcoming such difficulties; and it accomplishes its object by providing means for changing the relative positions of the drill bit and the reaming cutter; or, if several reaming cutters are used, for changing the relative positions of the cutters. How this is done in a specific preferred manner illustrative of the invention will be best understood by reference to the accompanying drawings, in which:

Fig. 1 is an elevation of my improved reamer and drill showing it in operation in a well;

Fig. 2 is an enlarged elevation, with parts in longitudinal section, of the reaming parts

of the tool, showing them in the position in which they pass through the well pipe;

Figs. 3, 4 and 5 are cross-sections on lines 3—3, 4—4 and 5—5, respectively, of Fig. 2;

Fig. 6 is an enlarged cross-section on line 6—6 of Fig. 1; and

Figs. 7 and 8 are bottom plans of the tool showing the two typical positions of the drill bit.

In the broader aspects of my invention it is immaterial what type of reaming cutter may be used, and also immaterial what specific type of drill bit; and accordingly the specific illustrations here shall not be taken as limitations upon the invention. I prefer to show reaming cutters of the roller type mounted upon suitable carriers; and I prefer to show a fish tail bit as illustrative of any type of flat bit which has the characteristics and capabilities hereinafter spoken of. Also the particular mountings for the reaming cutters and their carriers should be taken as illustrative and typical rather than as necessary limitation upon the broader aspects of my invention.

In the drawings I illustrate a suitable body or mandrel 10 formed at 11 at its upper end to connect with the usual rotary drill stem. At the lower end of this body the fish tail bit 12 is mounted in such a manner that it may turn between the two relative positions shown in Figs. 7 and 8. One of the reaming cutters, shown as the lowermost one in this particular case, is in this specific embodiment illustrated as being fixed in position upon the body; and thus it will be seen that, as between this lowermost reaming cutter and the bit, there is a relative capability of rotation so that in one position as shown in Fig. 8 the plane of the bit is parallel to the plane of offset of the cutter, and so that, as shown in Fig. 7, in another position the plane of the bit is substantially at right angles to the plane of offset of the cutter. This capability of relative rotation can be attained by having either the bit or the specified cutter relatively rotatable upon the body; and I prefer here to show the specified cutter as fixed upon the body and the bit as rotatable in position.

Thus the lowermost roller cutter 15 is shown as mounted upon a carrier sleeve 16 which is set by any suitable means, as by set screws 17, upon the interior body 10. Below the sleeve 16 there is a thrust sleeve 18; and below the lower end of this thrust sleeve the hollow socket 19 of drill bit 12 surrounds the lower end of the body, is rotatable around the axis of that lower end, and has up-thrust bearing against sleeve 18. The lower cylindrical and somewhat reduced end of the body is designated 10^a. In order to limit rotative movement of the drill bit to an angle of approximately 90°, and at the same time to give the drill bit good rotary driving connection with the body, I provide the drill bit socket 19 with two sets of arcuate slots 20 one of which is shown in detail in Fig. 6. Heavy stop pins 21 are set in the body and the heads 20 of these pins play in slots 20. Holes are provided through the socket wall to facilitate insertion of pins 21 after the socket is in place on the body, and these holes are closed by plugs 22 to prevent entry of mud or other 25 foreign matter. It will be seen that the pins and slots not only limit relative rotation of the drill bit but also support the drill bit on the body.

Reaming roller 15 projects outwardly at 30 one side of the tool beyond the periphery of carrier sleeve 16, this outward projection of the reaming roller being far enough to ream a hole substantially larger than that cut by drill bit 12 and substantially larger than the 35 interior of the casing through which the drill will pass, providing the tool as a whole is rotated about the central axis of the body. With the drill bit in the position of Fig. 7, with its plane substantially at right angles 40 to the plane of displacement of the reaming cutter 15, the tool can be passed through the pipe P because the drill bit, in that relative position, can be displaced far enough from the center of the pipe to allow the offset reaming roller 15 to pass through the pipe. Although the drill bit is preferably only of slightly less width than the interior diameter of the pipe, and its width is preferably greater than the diameter of the composite 50 body (the body which is made up of the body proper 10 and the sleeve 16) and although for these reasons the drill bit can only be displaced very slightly within the pipe in its own plane; it can be displaced a substantially 55 greater distance in a direction perpendicular to its own plane, as shown in Fig. 7. Thus with the parts in the relative position shown in Fig. 7 the tool will readily pass through the pipe.

60 But if drilling and reaming are attempted with the parts in the relative position of Fig. 7, the lateral thrust or drilling reaction against reaming cutter 15 will thrust the tool over (for instance toward the left in Fig. 1) and will thrust the drill bit over in that di-

rection if it is in the relative position shown in Fig. 7. However with the drill bit in the relative position shown in Fig. 8 and Fig. 1, such lateral thrust is prevented by the fact that the edge of the drill bit is in direct contact with the side of the hole so that it cannot be thrust over. Accordingly, in using this tool, the parts are put down through the pipe in the relative positions of Fig. 7, the drill bit being then in one of its limiting positions; and then by right-handed rotation of the drill stem the parts move to the relative positions shown in Figs. 1, 6 and 8, and drilling and reaming may be proceeded with, the reaming cutter 15 reaming the hole out to the full extent of its radial offset from the true center of the tool.

Although I have shown but one reaming cutter 15 arranged stationarily upon the body, it will be understood that any suitable number of such stationary cutters may be used all offset in substantially the same plane from the center of the body. However, I have preferred in this illustration of my invention to illustrate further and other cutters rotatable in position with reference to the body center so as to illustrate another aspect of my invention. Thus I show two upper cutters 15^a and 15^b mounted upon their respective carrier sleeves 16^a and 16^b. These two sleeves are rotatable within limits upon body 10. For instance the normally inoperative or contracted positions of the cutters being all in a line, as shown in Figs. 2 to 5, the sleeve 16^a is arranged to have a relative rotation of about 60° and sleeve 16^b a relative rotation of about 120°. Each sleeve is provided with two arcuate slots 30 or 30° and pins 31 are set in the body so that their heads play in these slots, plugs 32 closing the holes through which the pins are inserted. Spring 33 tends at all times to bring the parts back to the relative position shown in Fig. 2. These springs may be, as shown in the drawings, coiled torsion springs having one end, as shown at 34 in Fig. 2, set into the body, the springs surrounding a reduced body portion 35 and the other spring ends being secured to anchor pins 36 which are set through the wall of the sleeve 16^a or 16^b.

In the normal or contracted positions of the several cutters, all in line, and with the drill bit in the relative position shown in Fig. 7, the tool may be put down through pipe P as before explained. Then upon rotation of the tool not only is the drill bit turned to the relative position shown in Fig. 8, but the two upper cutters 15^a and 15^b are thrown around to the positions 60° and 120° removed from their normal positions. With the reaming cutters thus in equi-spaced relation about the center of the tool, the side thrust on the remaining cutters is equalized upon the tool as a whole and tendency to thrust the tool off laterally is minimized. But, whatever side

thrust there may be upon the lowermost cutter, unequalized at the level of that lowermost cutter and thus tending to shift the drill bit off laterally, is prevented from having any shifting effect upon the drill bit by its relative position as hereinbefore described.

5 The invention thus involves two characteristic features, one of which has to do with the relative positions of an offset reaming cutter or cutters and drill bit, and the other one having to do with the relative positions of the several reaming cutters.

10 The following claims are directed to such characteristics and also their combination.

15 I claim:

1. In a combined reamer and drill, the combination of a body, a reaming cutter offset to one side of the body axis, a drill of the flat type mounted on the body, and the mountings 20 of the drill and reaming cutter being such that they may be relatively rotated about the central longitudinal axis of the body between positions where the drill bit is substantially in the plane of offset of the reaming cutter 25 and where the drill bit is substantially perpendicular to that plane.

2. In a combined reamer and drill, the combination of a body, a reaming cutter offset to one side of the body axis, and a drill bit of the 30 flat type mounted upon the body for limited relative rotation about the central longitudinal axis of the body between a position substantially in the plane of offset of the reaming cutter and a position substantially at right 35 angles to said plane.

3. In a combined reamer and drill, a body, a reaming cutter rigidly mounted upon the body and offset beyond the body periphery in a certain plane of offset, a drill bit of the 40 flat type mounted on the lower end of the body to rotate on the central vertical axis of the body, said drill having a socket fitting over the lower end of the body, the body socket having arcuate slots and interengaging 45 pins which support the drill on the body and limit relative rotation of the drill bit to an angle of about 90°.

4. In a combined reamer and drill, a body, a reaming cutter rigidly mounted upon the 50 body and offset beyond the body periphery in a certain plane of offset, a drill bit of the flat type mounted on the lower end of the body, said drill having a socket fitting over the lower end of the body, the body socket 55 having arcuate slots and interengaging pins which support the drill on the body and limit relative rotation of the drill bit to an angle of about 90°, one of the limiting rotative positions of the drill bit being substantially in the 60 plane of the reaming cutter offset and the other limiting position being substantially at right angles to said plane.

5. In a reamer, the combination of a body 65 rotatable about a central axis, a plurality of cutter carriers mounted on said body, cutters

on said carriers, and one at least of said carriers being relatively and limitedly rotatable around the central longitudinal axis of the body, between a position where the cutters of the several carriers are in longitudinal 70 axial alinement and a position where the cutters are equi-angularly spaced about the body center.

6. In a reamer, the combination of a cylindric body rotatable about its central axis, a 75 plurality of cutter carrying sleeves mounted upon the body, cutters carried by said sleeves, and at least one of said sleeves being relatively and limitedly rotatable around the central longitudinal axis of the body between a position where its cutter is in longitudinal axial 80 alinement with another cutter and a position where said cutters are equi-angularly spaced about the axis of the body.

7. In a reamer, the combination of a cylindric body rotatable about its central axis, a plurality of cutter carrying sleeves mounted upon the body, cutters carried by said sleeves, and at least one of said sleeves being relatively and limitedly rotatable between a position where its cutter is in longitudinal axial alinement with another cutter and a position where said cutters are equi-angularly spaced about the axis of the body; one of said cutter carrying sleeves being fixed on the body, 95 another cutter carrying sleeve and the body being provided with arcuate slots and stop pins for allowing limited rotation of that sleeve with reference to the body, and a spring tending to rotate said last mentioned 100 sleeve on the body.

8. In a combined reamer and drill, the combination of a body, a drill bit mounted on the lower end of the body, a plurality of cutter carriers mounted on the body, cutters carried by said carriers offset beyond the body periphery at one side, said cutter carriers and said drill bit being limitedly relatively rotatable between positions where the several cutters are substantially in axial longitudinal 105 alinement and offset to one side of the body and the drill bit lies substantially at right angles to the plane of such cutter offset, and a position where the drill bit lies in a plane substantially perpendicular to the offset 110 plane of one of said cutters.

9. In a combined reamer and drill, the combination of a substantially cylindric body, a drill bit of the flat type limitedly mounted on the lower end of the body to turn between limiting positions separated about 90°, a cutter carrier fixed upon the body, a cutter on said carrier offset beyond the body periphery in a plane substantially parallel to the plane of the drill bit when in one of its limiting positions, another cutter carrier limitedly rotatively mounted on the body, an offset cutter on said carrier, said carrier being limitedly rotatable on the body between 115 a position in which its cutter is in longitudi- 120

125

130

nal alinement with the first mentioned cutter and a position in which the cutters are equi-angularly spaced about the center of the body.

- 5 10. In a combined reamer and drill, the combination of a substantially cylindric body, a drill bit of the flat type limitedly rotatively mounted on the lower end of the body to turn between limiting positions separated about 90° , a cutter carrier fixed upon the body, a cutter on said carrier offset beyond the body periphery in a plane substantially parallel to the plane of the drill bit when in one of its limiting positions, another 15 cutter carrier limitedly rotatively mounted on the body, an offset cutter on said carrier, said carrier being limitedly rotatable on the body between a position in which its cutter is in longitudinal alinement with the first 20 mentioned cutter and a position in which the cutters are equi-angularly spaced about the center of the body, rotation limiting means for the drill bit and the second mentioned carrier comprising pins and slots, a spring 25 tending to rotate the second mentioned carrier to the position in which its cutter is in longitudinal alinement with the first mentioned cutter.
11. In a combined reamer and drill, the 30 combination of a body, a drill bit mounted on the lower end of the body, a plurality of cutter carriers mounted on the body, cutters carried by said carriers offset beyond the body periphery at one side, said cutter carriers and said drill bit being limitedly relatively rotatable between positions where the several cutters are substantially in axial longitudinal alinement and offset to one side of the body and the drill bit lies substantially 35 at right angles to the plane of such cutter offset, and a position where the several cutters are substantially equi-angularly spaced 40 around the body.

In witness that I claim the foregoing I
45 have hereunto subscribed my name this 19
day of December, 1927.

JAMES J. SANTIAGO.
